[Term of Patent 14 years]

To all whom it may concern:

Be it known that I, HARRY S. BARTHOLOMEW, of Bristol, in the county of Hartford and State of Connecticut, have invented and produced a Design for a Curry-Comb Back, of which the following is a specification:

The nature of my design is fully represented in the accompanying engraving, to which reference is made.

A represents the outer portion of the curry-comb frame, which portion may be of any of the ordinary designs, and the teeth are secured

by rivets, in the usual manner. B represents the cross-bars or filling of the frame A, which filling is in the form of a horse.

I claim as my invention—
